UNITED STATES PATENT OFFICE.

JOHN A. FITZPATRICK AND GEORGE A. FITZPATRICK, OF SANTA ANA, CALIFORNIA
PROCESS OF DRILLING WELLS.

1,394,192.

Specification of Letters Patent.

Patented Oct. 18, 1921.

Application filed November 22, 1919. Serial No. 339,937.

To all whom it may concern:

Be it known that we, JOHN A. FITZPATRICK and GEORGE A. FITZPATRICK, citizens of the United States, residing at Santa Ana, 5 in the county of Orange and State of California, have invented new and useful Improvements in Processes of Drilling Wells, of which the following is a specification.

This invention relates to water and oil wells and has for its object to improve the method for drilling, developing and bringing in water and oil wells, and further has for its object to provide a method for the construction of a well that will enable the maximum efficiency in the draining of the subterranean reservoirs, and also that will result in the production of a well which will be operative for an extensive period by eliminating the ordinary causes tending to choke 20 the well inlets before the subterranean reservoirs have been fully exhausted, and with these and other objects in view the invention consists of the method of developing and constructing a well, and the well produced thereby, forms of which are illustrated in the accompanying drawings and described and claimed herein.

Figure 1 is a sectional view showing diagrammatically the earth strata penetrated 30 by a well hole.

Fig. 2 is a vertical section illustrating the same strata and hole and showing a step of the process in which the sand from the hole is being ejected and the inserted casing 35 is being jacketed in a sheath of gravel.

Fig. 3 illustrates the same hole and shows the casing perforating step of the process.

Fig. 4 is a vertical sectional view of the same hole showing the step of developing 40 the well.

Fig. 5 is a vertical section showing the well casing in completed condition with the usual operating pump installed in the pump pit.

Fig. 6 is a vertical section showing strata of earth different from that in Fig. 1 and illustrating the method as followed to produce an oil well.

Fig. 7 is a detail view of the shoe or foot 50 closure for the main casing.

In the ordinary process of drilling either shallow or deep wells either for water or for oil it is well-known that after the hole has been sunk and a casing inserted in the hole frequently the casing is crushed owing 55 to the excessive pressure of the caving earth

around the casing, and again it is well-known that the efficiency of a well is determined by the character of the strata of earth through which the well casing is passed, and often an expensive well will be rendered useless by the caving in of the walls of the well and crushing of the casing, and again rendered useless by infiltration of fine material as sand and silt through which the well casing is run, the silt and sand flowing into the suction perforations formed in the casing.

It is, therefore, one of the objects of our invention to provide a method for constructing a well in which the casing can be inserted and protected to a very material degree against crushing by inwardly falling walls of the well hole and which will also produce a well of maximum flowing efficiency.

To that end, the process involves the first step, as seen in Fig. 1, of drilling the hole 2 to the depth required as will be indicated according to the results shown by the log kept during the drilling of the well. This hole 2 is preferably made of considerably larger diameter than the casing 3 that is subsequently inserted, and in practice it is found that the well hole 2 can be drilled economically with the use of the co-called rotary drill apparatus although the hole may be drilled by any other suitable apparatus as determined by the nature of the earth's strata.

After the hole has been driven to the desired depth and has been given the desired diameter, as in Fig. 1, the upper portion of the hole being provided with a cross sectional area 2' is larger than the lower cross sectional area 2^a for the purpose of forming large passage ways, relatively, around the casing 3 which comprises, preferably, the upper casing portion 3^a known as the pump pit and the lower suction stringer 3^b. The pump pit section 3^a may be of any desired length and is connected to the water or lower stringer 3^b as by a reducer 3^c.

During the drilling of the well to produce the hole 2 in Fig. 1, the walls of the hole are usually sustained by the pressure of the mud 4 indicated therein and which is left in the hole during the drilling operation. After the hole has been drilled the drilling apparatus is withdrawn leaving the mud 4 in the hole and the casing 3 is then next assembled and lowered into the hole 2 to the desired depth, or in close proximity,

at its lower end to the bottom of the well; the lower end of the casing preferably being provided with a foot or shoe 5 with the downwardly opening perforations 6, Fig. 7, 5 to prevent any material quantity of the mud in the well from passing upwardly into the casing.

After the casing 3 has been lowered to the desired degree a reducer or swage nipple 10 7 is attached thereto and to this there is connected a water supply pipe 8 to which water under considerable pressure is delivered from any suitable source as a force pump, this water being driven downwardly 15 through the casing as indicated by the arrows, Fig. 2, and discharging through the perforated shoe 5 thus passing outwardly into the bottom of the well and rising upwardly in the considerable space surrounding the casing so that the upwardly moving 20 stream of water will carry the mud 4 formed by the previous drilling and also will tend by attrition from its circulation to work its way laterally into the various sand strata 25 indicated at 8 through which the well hole 2 may extend.

The attrition or scouring movement of the flowing water thus loosening the sand in the adjacent pockets and layers will carry 30 the loosened sand upwardly and discharge the same as at 10 at the top of the well.

An important feature of this invention is the continuous introduction into the well hole, while the water is being forced through 35 the supply pipe and down the casing, of a mass of gravel indicated at 11 this being of suitable size and assorted. We have found by actual practice that gravel of three-fourths of an inch diameter and less is preferable for the purpose and the gravel is introduced into the top of the well hole in 40 the spacing surrounding the casing 3 and will gravitate downwardly through the liquid mass of mud and water replacing the sand, silt and other fine particles by settling 45 upon the bottom of the well hole and gradually building up as the water displaces the finer particles.

As clearly illustrated at 12, the gravel 50 will flow laterally into such pockets as may have been passed through by the drill hole and will fill these pockets and also will fill the cavities produced by the erosion of the sand strata, this filling taking place in successive 55 upward deposit of the gravel during the continued washing of the well hole by the stream of water forced through the casing until the hole has been filled to the top with the gravel.

It has been found that the gravel will 60 thus settle laterally into the pockets by actual observation in drilling a well and developing the same according to this process by keeping a log of the steps and in 65 which it has been shown that a very con-

siderable quantity of gravel will often be required at some particular level in the well without any appreciable change in the height of the pile or jacket of gravel about the casing and on the contrary when the 70 gravel appears to be filling only the space immediately about the jacket the change is rapidly noted as determined by the quantity of gravel that may be poured into the hole.

Having thus filled the chambers or pockets in the strata and filled the space in the well hole about the casing 3 so that a gravel filtering jacket and mass is produced up to the top of the well then the pump connections are removed including the cap 7 and 75 any suitable perforating apparatus indicated at 15 is introduced into the well casing, and the lower portion or stringer 3^b is, preferably, perforated as at 13 from the top of the stringer below the reducer 3^c 80 down to the bottom of the casing. These perforations may be of any suitable proportions and size and are, preferably, less in one dimension than the size of the larger gravels in the mass charged into the well 85 hole.

After the perforating has been completed the perforating apparatus is removed and then the well is developed by introducing into the casing 3 a suction pipe 16, 90 preferably, of less diameter than the diameter of the stringer section 3^b, and this suction pipe is extended down to a suitable depth and an air supply pipe 17 is introduced into the same, this pipe being of less diameter 100 than the suction pipe 16 so that when air is forced into the pipe 17 it will discharge at the lower end thereof as at 18 into the suction pipe 16, the latter being imperforate but open at its lower end at 19, Fig. 4, so 105 that the action of the air discharging at 18 of the air pipe 17 will induce an upflow in the suction pipe of the water in the casing and of the water surrounding the casing in through the perforations 13 of the casing. 110 As the casing and gravel jacket is cleaned of sand by the air lift the pipe 16 will be lowered in successive steps until the entire depth of the well has been washed. The result will be that all of the sand that may 115 have accumulated in the casing is removed from the same by the air lift method and discharged at the outlet 20 of the suction pipe. This developing of the well continues for a suitable length of time until it is 120 proved that the well casing and the surrounding well chamber and pockets which are filled with gravel have been washed clear of sand and only clear fluid is being discharged at the outlet 20.

After this development of the well the suction pipe and the air lift pipe are removed from the well casing and any suitable form of pumping apparatus is connected to the casing, as for instance by inserting a 130

centrifugal pump 21 into the pump pit or section 3^a of the casing, and after the pump is set in operation the well will continue to flow with maximum capacity and with freedom from sand.

- When this method is followed for bringing in an oil well as is indicated in Fig. 6, it is desirable to prevent infiltration of water with the oil from the water bearing strata 10 above the oil bearing strata indicated at 25, Fig. 6; and to that end, in the original drilling of the hole 3 for an oil well after the drilling has been continued down to a suitable depth and taken through the usual 15 water bearing strata there is introduced into the hole an outer casing or shell 30 of somewhat less diameter than the upper portion of the well hole, and this casing is then externally packed with a cement jacket 31 to 20 prevent the downward flow of the water from the upper levels into the lower portion of the well hole indicated at 32 below the jacket and casing 31-30.

The jacket and casing are usually placed 25 in a stratum of earth that is impervious to water flow. From this it will be seen that by our method it is possible to perforate the lower end of the casing in the oil well from the portion immediately below the 30 jacket 31 to the foot of the casing section so that the oil reservoirs irrespective of their depths can all be drained into the suction apertures of the casing and yet the inflow of water from the upper layers be eliminated. 35 Again by jacketing the suction end of the casing with the gravel 11 as above described it will be seen that sand will be kept out of the casing and the oil will have free passage through the interstices in the gravel 40 mass.

By developing a well as disclosed in the above it will be seen that the well casing can readily be brought to a true vertical or plumb position within the well hole since 45 the latter is of sufficiently large diameter from top to bottom to permit the free suspension of the casing within the same and,

therefore, the usual difficulty encountered by the jamming of the pump within the casing is overcome. A further advantage 50 of this plumb position is in the reducing of wearing in the bearings.

While it has been stated that gravel is used in the method of producing the desired filter yet it is understood that any other filtering medium or agency may be utilized.

In order to secure the solid packing or settling of the gravel mass while the same is being charged into the hole the well casing, which is flexibly suspended in the well 60 hole, can be and sometimes is rotated.

Various changes may be made without departing from the spirit of our invention as claimed,

We claim:

1. That method, of constructing a well wherein a casing is lowered into a hole of greater diameter, from top to bottom than the casing, forcing water down the casing to the bottom of the well so it flows upward in 70 the outer chamber and washes it out, and filling the washed well hole with assorted bodies to form a filtering jacket about the casing, thereafter perforating the casing to form suction holes.

2. That method, of constructing a well wherein a casing is lowered into a hole of greater diameter, from top to bottom than the casing, forcing water down the casing to the bottom of the well so it flows upward 80 in the outer chamber and washes it out, and filling the washed well hole with assorted bodies to form a filtering jacket about the casing, thereafter perforating the casing to form suction holes, and then producing a 85 suction through the holes by an air lift to rapidly develop the well by draining off the small particles from the filtering jacket so that the liquid from the strata may percolate readily to the well casing.

In testimony whereof we have signed our names to this specification.

JOHN A. FITZPATRICK,
GEORGE A. FITZPATRICK.
